CLAIM

The ornamental design for a charge-port door, as shown and described.

DESCRIPTION

FIG. 1 is a perspective view of a charge-port door.

FIG. 2 is a front elevational view of the charge-port door of FIG. 1.

FIG. 3 is a back elevational view of the charge-port door of FIG. 1.

FIG. 4 is a side elevational view of the charge-port door of FIG. 1.

FIG. 5 is a side elevational view of the charge-port door of FIG. 1 from the opposite side from FIG. 4.

FIG. 6 is a top plan view of the charge-port door of FIG. 1.

FIG. 7 is a bottom plan view of the charge-port door of FIG. 1; and,

FIG. 8 is a perspective view of the charge-port door of FIG. 1 as part of a semi-truck cab.

The items shown with broken lines form no part of the claimed design.
